MOBILE VIDEO TAPE RECORDER CART

Norman R. Selinger, 7727 Groton Road, Bethesda,
Md. 20014, and David C. Herbert, 12618 Kornett
Lane, Bowie, Md. 20715

Filed Oct. 18, 1967, Ser. No. 9,053

Term of patent 14 years

U.S. Cl. D33—14
Int. Cl. D6—01

FIG.1

FIG.2

FIG.3

FIG.4

FIGURE 1 is a front perspective view of the mobile video tape recorder cart with leaves in horizontal position resting on their respective handles.

FIGURE 2 is a front perspective view of the mobile video tape recorder cart with the leaves in vertical position.

FIGURE 3 is a front plan view with leaves lying on the top working surface.

FIGURE 4 is a side view. The reverse side is substantially identical to the side illustrated.

The back of the mobile video tape recorder cart is plain and unornamented.

We claim:

The ornamental design for a mobile video tape recorder cart, substantially as shown and described.
